UNITED STATES PATENT OFFICE.

SAMUEL J. RAWLINGS, OF KEARNY, NEW JERSEY.

DOOR HOLDER.

Application filed August 11, 1920. Serial No. 402,766.

To all whom it may concern:

Be it known that I, SAMUEL J. RAWLINGS, a citizen of the United States, residing at Kearny, in the county of Hudson and State 5 of New Jersey, have invented certain new and useful Improvements in Door Holders, of which the following is a specification, reference being had to the accompanying drawings.

10 This invention relates to certain improvements in door holders and has relation more particularly to a device of this general character adapted automatically to secure a door or the like in its open position, and it 15 is an object of the invention to provide a device of this general character including a pivotally mounted latch, together with novel and improved means to protect the pivotal connection of the latch from dirt or the like 20 and wherein said means also serves as a stop to prevent the latch from passing too far back over the center of gravity.

Another object of the invention is to provide a novel and improved holder of this 25 general character including a pivoted latch coacting with a catch and wherein the latch is provided with means engageable with the catch for positively swinging the latch upwardly.

30 An additional object of the invention is to provide a novel and improved holder of this general character comprising a coacting latch and catch, together with a plunger which, in addition to serving as a buffer, 35 operates effectively to facilitate the desired separation or disengagement of the latch and catch.

The invention consists in the details of construction and in the combination and 40 arrangement of the several parts of my improved door holder whereby certain important advantages are attained and device rendered simpler, less expensive and otherwise more convenient and advantageous for 45 use, as will be hereinafter more fully set forth.

The novel features of my invention will hereinafter be definitely claimed.

In order that my invention may be the 50 better understood, I will now proceed to describe the same with reference to the accompanying drawings, wherein:

Figure 1 is a view partly in side elevation and partly in section illustrating a door 55 holder constructed in accordance with an embodiment of my invention.

Figure 2 is a view in top plan of the structure as illustrated in Figure 1, and

Figure 3 is a vertical sectional view with parts in elevation taken through the rear 60 portion of the latch and the supporting member therefor.

As disclosed in the accompanying drawings, C denotes a catch comprising a plate 1 adapted to be suitably secured in applied 65 position to a door D or the like and extending outwardly from the plate 1 at right angles thereto is a tongue 2, the outer end portion of which terminates in a hook 3, between which latter and the plate 1 is formed 70 a notch or recess 4. The outer face 5 of the hook 3 is inclined downwardly and forwardly and the notch or recess 4 is likewise inclined and substantially in parallelism with the inclination of the outer face 5. 75

M denotes a shell-like body member or socket provided at one end with the oppositely directed wings 6 to provide means whereby said member M may be suitably secured to a wall W or kindred surface. The 80 member M is substantially U-shaped in cross section and the rear portions of the side walls or plates 7 thereof are provided with the inwardly disposed flanges or ribs 8 having their opposed faces flat and extending 85 upwardly from the base 9 of the member M and bridging the space between the lower portions of the flanges or ribs 8 is a flange 10 for a purpose to be hereinafter more particularly referred to. 90

The upper end portions of the flanges or ribs 8 and the adjacent portions of the side walls or plates 7 are provided with the upstanding ears 11 substantially arcuate in form and having their peripheries substantially concentric to a pin 12 bridging the space between the flanges or ribs 8 and having its extremities supported by the side walls or plates 7 of the member M.

L denotes a latch provided at its rear end 100 portion with a perforate lug 14 substantially snugly fitting between the upper portions of the flanges or ribs 8 and through which is directed the pin 12 whereby the latch L is pivotally supported. The end portion of 105 the latch L at its pivoted extremity is arcuate in form with the side marginal portions thereof overlying the ears 11, whereby an effective means is provided to protect the hinge or pivotal connection of the latch L 110 from dirt or the like and particularly to prevent paint from getting to such connec-

tion when painting the wall or other surface to which the member M may be attached.

The side marginal portions of the latch L at its pivoted extremity also provide means

5 whereby the latch may be held from passing upwardly too far past the center of gravity as said marginal portions are adapted to contact with the rear faces of the ribs or flanges 8. In order to facilitate this last 10 operation or functioning the ribs or flanges 8 are positioned a slight distance inwardly of the rear or back end of the member M, resulting in a vertically disposed recess or channel 15 open at both ends.

15 The forward or free end portion of the latch L is provided with an opening 16, preferably rectangular in form. The rear or inner wall 17 defining the opening 16 is on an upward and forward incline or bevel. 20 The latch L operates by gravity and the opening 16 thereof is adapted to receive the upwardly directed hook 3 of the catch C as will hereinafter be more particularly set forth.

25 Depending from the inner end portion of the latch L is a lug 18 having flat side faces disposed in a direction longitudinally of the latch L and having its rear edge 19 straight and substantially perpendicular with respect 30 to the pin 12. The rear edge 19 is adapted to contact with the flange 10 whereby the downward or gravity movement of the latch L is limited. The forward marginal edge a of the lug 18 is rounded or arcuate and 35 cooperates with the outer face or edge 5 of the hook 3 in a manner to be hereinafter referred to.

The base 9 of the member M is tubular and the outer end of the bore 20 is defined 40 by an inwardly directed flange 21 while the opposite or inner end thereof is closed by a plug or head 22 threaded therein. Slidably arranged within the bore 20 for rectilinear movement is a plunger P. The inner or inserted end of the plunger P is defined by an outstanding flange 23 adapted to engage the flange 21 whereby the outward movement of the plunger P is limited.

45 Arranged within the bore 20 and interposed between the inner end of the plunger P and the plug or head 22 is an expansible member 24, preferably a coil spring, which operates to constantly urge the plunger P outwardly, the tension of said member or 50 spring being increased or decreased as the occasions of practice may require by adjusting the plug or head 22. The outer end portion 25 of the plunger P is preferably rounded.

60 When the door D or the like upon which the catch C is mounted is opened sufficiently, the outer inclined edge or face 5 will contact with the outer rounded end 26 of the latch L, resulting in the latch L being raised 65 sufficiently to permit the hook 3, when the

latch L drops by gravity, to extend through the opening 16 whereby the door D or the like will be held positively in its open position.

Before the latch L drops, the plate 1 of 70 the catch C, or more particularly the downwardly extending portion 27 thereof, will abut or contact with the outer or rounded end portion 25 of the plunger P, so that the plunger P is moved inwardly and placed 75 under tension before the latch L drops so that when the latch L is in holding engagement with the hook 3, the plunger P operates to prevent any rattling that might be produced between the latch L and the hook 80 3 by a slight movement of the door D or the like.

When it is desired to release the latch L from the hook 3, the door D or the like is pushed against the plunger P, placing the 85 same under great tension and at the same time the inclined edge or face 5 of the hook 3 contacts with the rounded edge a of the lug 18 whereby the latch L is thrown upwardly, said latch L being prevented from 90 swinging upwardly and too far beyond the center of the gravity by contact of the pivoted end of the latch L with the outer or rear faces of the flanges or ribs 8, so that the return or downward movement of the latch L will occur automatically by gravity and which gravity movement is further assured 95 by the additional weight afforded by the lug 18.

After the door D or the like has been 100 swung inwardly to effect the requisite raising of the latch L, the pressure upon the door D or the like is released, whereupon the outward movement of the plunger P under the influence of the expansible member 105 or spring 24 will automatically swing the door D or the like outwardly or in a direction away from the member M at such speed and to such extent that when the latch L drops, the hook 3 of the catch will be positioned a sufficient distance in advance of the outer or free end of the latch L to prevent the hook 3 from again passing through the opening 16.

110 It is to be particularly noted that the mounting of the plunger P is such that the expansible member or spring 24 is effectively protected from water, dirt or the like which would otherwise interfere with the efficiency of the spring.

115 From the foregoing description it is thought to be obvious that a door holder constructed in accordance with my invention is particularly well adapted for use by reason of the convenience and facility with which it may be assembled and operated, and it will also be obvious that my invention is susceptible of some change and modification without departing from the principle and 120 spirit thereof and for this reason I do not 130

wish to be understood as limiting myself to the precise arrangement and formation of the several parts herein shown in carrying out my invention in practice except as hereininafter claimed.

I claim:

1. A holder of the class described comprising, in combination, a member including a base, upstanding side plates and a flange extending upwardly from the base adjacent the rear ends of the side plates, a gravity operated latch pivotally engaged between the upper portions of the side plates at the rear thereof, a lug depending from the latch member and extending longitudinally thereof, the forward edge of the lug being rounded, the rear edge of the lug being straight and of a length to engage the flange of the base to limit the gravity movement of the latch member, and a hook member with which the latch engages by gravity, the rounded edge of the lug having contact with

the hook member to facilitate the disengagement of the latch member from the hook member.

25

2. A holder of the class described comprising in combination, a member including spaced side plates, said plates being provided with opposed ribs inwardly directed, said ribs being continued by upstanding rounded ears, a latch member working between the plates, means coacting with the ears and the latch member for supporting the latch member for pivotal movement, the curvature of the ears being substantially concentric to the axis of such pivotal connection, said latch member at its pivotal portion having its side marginal portions overlying the ears to provide shields for the pivotal connection.

30

In testimony whereof I hereunto affix my signature.

35

SAMUEL J. RAWLINGS.
